UNITED STATES PATENT OFFICE.

WILLIAM T. McCULLOUGH, OF CHICAGO, ILLINOIS, ASSIGNOR TO GOODMAN MANUFACTURING COMPANY, OF CHICAGO, ILLINOIS, A CORPORATION OF ILLINOIS.

MINING MACHINE.

Continuation of application Serial No. 434,591, filed January 3, 1921. This application filed December 29, 1922, Serial No. 609,617. Renewed March 5, 1928.

This invention relates to mining machines of the continuous cutter type, which are adapted to be fed and guided during the cutting operation by means of suitable draft cables anchored at a distance from the machine. More specifically, the present invention relates to an improved form of mining machine of the class shown and described in the application of Charles E. Davis, Serial No. 374,746, filed April 17th, 1920, in which a mining machine of the continuous cutter type is provided with two cable drums similarly constructed, and each adapted to be either driven by the mining machine motor 10 to wind the draft cable on the drum or to pay out the cable from the drum in the opposite direction under control of the retarding device associated therewith.

The object of the present invention is to provide an improved construction of cable drum for a machine of the class above referred to. This application is a continuation of the application of William T. McCullough, Serial No. 434, 591, filed January 25 3rd, 1921, combined with the description embodied in the application of Charles E. Davis, above referred to, to which the improved form of cable drum has been applied.

In the embodiment herein described, which illustrates one of several forms which my invention may take, I have shown two rope drums, one of which is adapted to be normally driven, and the other of which is provided with a retarding means comprising a friction-controlled releasing device. However, I find that certain additional advantages in the guiding and manipulation of the machine are obtained by a construction in which the normal functions of the two drums 35 may be mutually reversed at certain times, particularly as the machine is approaching and leaving the normal cutting position. Accordingly, in the present invention, I provide means whereby the drum which is normally the tail-rope drum may be positively driven by the motor, while the other drum is simultaneously disconnected from the motor and allowed to be released by an adjustable friction device. I also provide variable speed mechanism affording operative connection at will between the motor and either of the two drums.

The main purpose in thus reversing the functions of the rope drums is to facilitate

the movement of the machine as it is being applied to, and withdrawn from, the working face, and to eliminate certain replacements of the rope anchors which are necessary with the ordinary type of machine, thereby affording a more continuous movement of the machine. A distinction must therefore be made between the temporary reversal of the functions of the drums for the purpose stated above, and a complete reversal of the direction of cutting. The functions of the drums 65 may be temporarily reversed without effecting any change in the normal direction of movement of the cutting apparatus.

Furthermore, the present invention should be distinguished from that class of machines 7 which also have driving connections with both feed and tail-rope drums, but in which the drums are simultaneously driven in opposite directions so that the tail-rope is paid out at the same rate that the feed rope is wound in, for the purpose of maintaining a right-angled relation of the machine to the face during the cutting operation. As will appear in the description of the operation of the present invention, the manipulation of the machine while approaching and leaving the work usually requires respective rates of movement of the two drums which vary so greatly that a device in which the drums are driven simultaneously as above described 30 would be useless and inoperative for the purposes of the present invention.

In feeding and guiding a mining machine, one cable drum is normally adapted to be driven in one direction by suitable gearing 35 connected with the mining machine motor, to wind up a draft cable thereon, while a second drum, similarly constructed but disconnected from the motor, is allowed to rotate in the direction to pay out the cable therefrom under control of the manually controlled retarding device, such as a friction band. It has been found advisable however, under certain conditions to reverse the normal functions of the two drums; that is to say, the normally driven drum is disconnected from the motor by suitable clutch means and is allowed to rotate in the opposite direction to pay out the cable under control of a retarding device, while the opposite drum becomes motor driven. In other words, I contemplate that the mining machine is to be provided with two drums of

the construction shown and described in the present invention, each of which is provided with a driving mechanism and a retarding device. It will be seen, from the following description, that means are provided for automatically engaging the retarding device with the drum when the latter is moved in the direction opposite to that in which it is adapted to be driven, and similarly, the retarding device is automatically disengaged when the drum is driven in its normal direction by the motor. Furthermore, means are provided whereby the driving and retarding engagements may be reversed so as to be applied in the opposite directions, respectively; that is to say, the drum may either be driven in a clockwise, and released in counter-clockwise direction, or vice versa, as desired. Means are also provided for allowing the drum to be turned by hand in either direction.

Other objects of the invention will appear from time to time as the description proceeds.

The invention consists in the combination, construction and arrangement of the parts as will hereinafter be described in connection with the accompanying drawings and more particularly defined in the appended claims.

In the drawings, Figure 1 is a plan view of the machine in normal cutting position.

Figure 2 is a rear elevation of the driving mechanism, drawn to a larger scale than Figure 1.

Figure 3 is a right side elevation of the driving mechanism drawn to the same scale as Figure 2.

Figure 4 is an enlarged plan view of the mechanism shown in Figure 3, showing some of the details in section.

Figure 5 is an end view of the cable drum.

Figure 6 is a section of the drum taken on line 6—6 of Figure 5.

Figure 7 is a section of the drum taken on line 7—7 of Figure 5.

Figure 8 is a section of the drum taken on line 8—8 of Figure 7, and

Figure 9 is a detail.

My invention is shown as applied to a mining machine having a main frame A, and a cutting element 1 projecting therefrom. This cutting element is preferably provided with an endless cutter chain C of the usual pattern, which is driven by the motor B, to cut a horizontal kerf in the mine wall as the machine advances. The cutter chain C may be reversed to cut in either direction, and driven in the reverse direction by reversing the motor.

Figure 1 shows the arrangement of the machine and control ropes during the normal cutting operation across the working face. A rope 2 is adapted to be wound on a drum 3, mounted on the left side of the machine frame A. Said rope passes from said drum over a pulley 4 adjacent the front end of the

machine frame, and thence to a suitable anchor 5, fixed at a distance from the machine, and near the working face along which the machine is to be moved. A second rope 6 is anchored at the opposite end of the working face, and is led over suitably arranged pulleys 7 and 8, at the rear end of the machine frame, to a second drum 9, on the right side of the machine. The arrangement is such that in the normal cutting position illustrated in this figure, the rope drum 3 is connected thru driving mechanism, to be hereinafter described, to the motor B. The opposite drum 9 is disconnected from the driving mechanism, and during the normal cut across the face, is released at a rate substantially the same as the rate of take-up on the rope 2, by means of an adjustable friction band device 10 on the drum 9. The purpose of the rope 6 is to restrain the movement of the rear end of the machine, and maintain the proper angular relation of the cutter bar to the working face.

Referring now more particularly to details of the mining machine shown, means are provided for reversing the normal functions of the two drums above described, whereby the drum 9 may have a driving connection with the motor, and the other drum 3 may be released thru a friction device 11 similar to the friction device 10 above described.

The functions of the two drums being therefore mutually reversible, I find it preferable to make the drums identical in construction.

The main elements of the driving mechanism for drums 3 and 9 comprise a longitudinal shaft 12 geared to the motor B, a worm gear 13 actuated by said longitudinal shaft, a variable speed mechanism 14, and an endwise movable shaft 15 driven by said variable speed mechanism, and provided with interlocking clutches 16 and 17 on opposite end thereof. The driving connection between clutch 16 and the drum 3 comprises a shaft 18, driving pinion 19 and gear ring 20 on said drum. The driving connection between clutch 17 and the drum 9, comprises a pinion 21, idler gear 22, and a gear ring 23 on the latter drum. The purpose of the idler gear 22 is to drive said drum in a direction opposite to that of the other drum 3.

The variable speed mechanism 14 is preferably of the planetary type, provided with an external friction band 14^a, and a friction adjusting handle 14^b, for the purpose of transmitting variable speeds to the shaft 15. Details of this mechanism need not be described excepting to indicate a clutch member 24 feathered on the shaft 15, and provided with clutch jaws 25, 25 adapted to be engaged either with a high speed member 26, or low speed member 27 of the planetary gear 14. The clutch member 24 is provided with a shifter yoke 28, and a control

handle 29 attached thereto. Although I have shown a planetary gear variable speed mechanism, it will be understood that as far as the broader features of my invention are concerned any equivalent variable speed device may be substituted therefor.

The endwise movable shaft 15 extends thru the variable speed mechanism 14 and worm gear 13 to form an axial bearing therewith. 10 The clutch 16 on the left end of said shaft comprises an annular flange 30 on said shaft, provided with clutch jaws 31, 31, adapted to engage with corresponding clutch jaws 32, 32 on the connecting shaft 18 extending 15 to the left hand drum 3. The shaft 15 is also provided with a recess 33 in which a reduced portion 34 of the connecting shaft 18 extends, for the purpose of maintaining the two shafts in alignment with each other. 20 The clutch 17 for connecting the shaft 15 to the right hand drum 9 is located adjacent the interior face of the pinion 21 on the right hand side of the machine. Said clutch comprises a sleeve 35 fixed to the shaft 25 15 and extending thru the pinion 21 to form an axial bearing therewith. Clutch jaws 36, 36 are carried by said sleeve, and are adapted to engage corresponding clutch jaws 37, 37, preferably formed integral with the pinion 21. Means for shifting the shaft 30 15 comprises a shifter yoke 38 mounted on the sleeve 35, provided with a shifter arm 38^a, which is operated by a suitable control handle 39, (see Figure 2). In the position 35 shown in Figures 2, 3, and 4, the shaft 15 is in neutral position, that is to say, clutches 16 and 17 are both disengaged. It will be seen that if the control handle 39 is moved downwardly, the shaft 15 will be 40 moved longitudinally so as to engage the clutch 16 to form a driving connection with the rope drum 3. On the other hand, if the control handle is moved upwardly, the shaft will be moved in the opposite direction, clutch 16 will be disengaged and the opposite clutch 17 will become engaged to form a driving connection with drum 9.

The rope drums 3 and 9, as hereinbefore pointed out, are preferably identical in construction, so that a detailed description of one of the drums will apply to both.

Referring now more particularly to the novel features of my invention, the drum 3 comprises a hub 40, a web 41, a channel portion 42 extending in one direction to receive the cable, and a rim 43 extending in the opposite direction from the web as shown. The hub 40 is mounted on a suitable bearing pin 44 carried by a stud 45 on the machine. An end plate 43^a is provided to enclose the inner end of the drum.

The driving gear ring 20 is loosely mounted on the rim 43 of the drum and has a plurality of notches 47, 47 spaced about 65 the interior surface thereof. In the device

illustrated, the driving gear ring is provided with four of such notches. A pawl 48 is mounted on a rocking pin 50, and each end of said pawl is adapted to extend through suitable apertures 51, 51 in the flanged rim 43 to engage with the notched surface of the gear ring 20. The rocking pin 50 bears at one end in a support 52 projecting from the rim 43 and extends through the web 41 of the drum. A cam member 53 is affixed to the outer end of pin 50, adjacent the outer face of the web 41 as shown in Figure 7. Said cam member is provided with an elongated face extending longitudinally 75 of the pawl 48 with which it is associated as shown in detail in Figure 9.

The friction device 10 is mounted adjacent the gear ring 20 on the rim 43 and comprises a friction ring 54 and a friction band 56 of any suitable pattern adapted to be manually controlled in any well known manner. The friction ring 54 is loosely mounted on the flanged rim 43 and is provided with a ratchet and pawl device similar to that hereinbefore described in connection with the gear ring 20. Said ratchet and pawl device comprises notches 57, 57 on the friction ring, a pawl 58, rocking pin 59, and cam member 60. The two sets of pawls and cams are preferably arranged on opposite sides 85 of the hub as shown.

Means for controlling the movement of the pawls comprises an annular ring 61 mounted on the outer end of the drum hub 40 and carrying a pair of tension members 100 62, 62 adapted to engage the cams 53 and 60 respectively as shown in Figure 5. Said tension members each comprise an endwise movable pin 63 seated in a socket 64 formed in the periphery of the ring 61 and having a compression spring 64^a mounted within said socket tending to force said pin 63 outwardly to engage its respective pawl, as shown in Figure 9. The ring 61 is provided with a plurality of fingers 65, 65 spaced about its periphery so positioned in the recessed face of the drum as to be easily reached by the operator when it is desired to shift the tension devices 62, 62 in relation to the cam members, and reverse the 115 pawls.

It will be observed that the pawl 58 is normally inclined to the friction ring 54 in the same direction as that of the driving pawl 48, as shown in Figure 8. When the pawls are in this position, the gear ring 20 is driven by suitable operative connections in a clockwise direction, and the pawl 48 becomes engaged in one of the notches 47 so as to drive the drum therewith. Similarly, 120 the pawl 58 becomes released so that the drum may be driven independently of the friction device. When the driving connection to the motor is disconnected, the drum is free to move in the opposite or counter- 130

clockwise direction until the pawl 58 engages with a notch 57 in the friction ring 54. The rope on the drum can then be paid off only against the friction imposed by the band 56, which friction may be regulated in any suitable manner as before described. If power is again applied to the gear ring 20 it will again move in a clockwise direction until pawl 48 engages a notch 47 as before, 10 to form an operative connection between said gear ring and the drum. It will thus be seen that the drum may alternately be driven in one direction or released against friction in the opposite direction.

15 Whenever it is desired to reverse the direction of driving the drum, either to reverse the direction of movement of the mining machine, or for any other purpose, the pawls 48 and 58 may be rocked about their axes by 20 manipulation of the ring 61, (see Figure 5), so as to transpose the tension devices 62, 62 from one end of the cams 53 and 60 over their respective centers, and to the opposite ends thereof. This movement of the tension 25 devices will cause the pawls to be rocked so as to bring their opposite ends into operative engagement with the driving ring and friction ring respectively. By means of this arrangement, the operator may reverse both 30 pawls simultaneously. Any suitable means for limiting the movement of the ring 61 respective to the drum may be provided.

I also provide means whereby the drum may be rotated by hand, independent of the 35 driving mechanism when desired. This means comprises a bracket 66 rotatably mounted on the end of the bearing pin 44 and having a shoulder 67 thereof adapted to engage and retain the outer face of the 40 control ring 61. A nut 66^a retains said bracket on the pin 44. Said bracket is provided with a pair of laterally extending arms 68, 68 between which a ratchet arm 69 is pivotally mounted on a pin 70. Said ratchet arm extends 45 transversely of the axis of the drum and preferably is positioned within the boundary of the recessed face thereof, as shown in Figure 6. Means are provided for maintaining said arm in this position which 50 comprises a rod 71 extending longitudinally through the bearing pin 44 and a suitable slot 72 in said arm. The rod 71 is provided at one end with a retaining member 73 adapted to engage the outer face of said arm, 55 and a compression spring 74 at the opposite end adapted to engage a shoulder 75 within the pin 44 so as to normally maintain ratchet arm 69 in the position shown in full lines in Figure 6. Whenever it is desired to operate 60 the ratchet arm, it may be swung outwardly to a position indicated in dotted lines in Figure 6 in which position a lug 76 at the outer end thereof may be engaged with any one of the lugs 77, 77 arranged about the outer 65 face of the drum portion 42, (see Figure 5).

A crow-bar or other suitable device may be inserted in a socket 78 formed in the outer end of the ratchet arm to provide a greater leverage for rotating the drum in this manner.

70 From the above description, it will be clear that I have provided a simple and durable construction of cable drum in which the pawl mechanism is entirely enclosed and protected from the dust, dirt and other foreign accumulations. The adjusting mechanisms for the pawls and the ratchet mechanism for turning the drum by hand are both nested in the recessed face of the drum, but in view of, and easily accessible to the operator. 75 When it is desired to reverse or actuate the pawls, one of the fingers 65, 65 will always be in position where it may be easily reached to rotate the control ring 61 associated with the tension devices 62, 62. If it is desired to temporarily disengage the pawls, the tension device 62 may be moved into alignment with the axes of said pawls, that is to say, to the center of the cams 53 and 60 so as to maintain the pawls out of engagement 80 in either direction.

85 The pawls are interlocked so as to be operable simultaneously, and are thus maintained in proper relation with each other so as to provide the desired driving engagement with the ring 20 in one direction of movement thereof so as to wind up the rope on the drum, and an automatic engagement with the friction or retarding device when the drum is moved in the opposite direction to 90 unwind the rope. The pawls may also be simultaneously moved into an inoperative position, to allow the drum to be rotated freely in either direction. Furthermore, in case it is desired to reverse the direction of 95 cutting of the entire machine, together with the cutter chain, to cut in the opposite direction, the pawls may be reversed by a single movement of the ring 61.

100 Although I have shown and described one form in which my invention may be embodied, it will be understood that many other means may be employed for accomplishing the same results, without departing from the spirit and scope of my invention. 105 I do not therefore wish to be understood as limiting myself to the specific construction illustrated herein excepting as specifically limited in the appended claims.

110 I claim as my invention:

1. In a mining machine the combination 115 of two winding drums each associated with a flexible cable, driving means operable to rotate each of said drums in a direction to wind its cable thereon, retarding means operable to automatically engage each of said drums when it is rotated to unwind its cable thereon, and means associated with each 120 drum for simultaneously disengaging both driving means, and retarding means where- 125 130

by the cable may be unwound freely of said driving and retarding means.

2. In a mining machine provided with cutting mechanism extending longitudinally therefrom, the combination of two winding drums each associated with a flexible cable, a motor, and driving means between said motor and each of said drums, a ratchet and pawl device adapted in one position to drive each of said drums in one direction, a retarding device associated with each drum, and a second ratchet and pawl device on each drum, adapted in one position to operatively connect said retarding device with said drum when the latter is rotated in a direction opposite to that in which it is driven, and interlocking means connecting both of said ratchet and pawl devices to control both devices simultaneously, whereby they may be maintained in proper relation one to the other as aforesaid.
3. In a mining machine provided with reversible cutting mechanism extending longitudinally therefrom, the combination of two winding drums each associated with
- a flexible cable, a motor, and reversible driving means between said motor and each of said drums consisting of a reversible ratchet and pawl device affording operative connection between said driving means and each of said drums to rotate the latter in either direction, a retarding device associated with each drum, and a second reversible ratchet and pawl device on each drum affording an operative connection between said retarding means and said drum in either direction of rotation of the latter, and interlocking means connecting the ratchet and pawl devices associated with each drum to maintain them in a predetermined relation where- by the drum may be driven at will in either direction independent of the retarding device and upon cessation of such driving may be rotated in the opposite direction in operative connection with the retarding device. 45

Signed at Chicago, in the county of Cook and State of Illinois, this 27th day of December, 1922.

WILLIAM T. McCULLOUGH.
